UNITED STATES PATENT OFFICE.

ROBERT L. GRAY, OF NEWARK, NEW JERSEY, ASSIGNOR TO ROSE LITHOGRAPHIC CORPORATION, OF NEW YORK, N. Y., A CORPORATION OF NEW YORK.

BOX OR CARTON FOR DISPLAYING MERCHANDISE.

1,334,932.

Specification of Letters Patent. Patented Mar. 23, 1920.

Application filed August 13, 1918. Serial No. 249,748.

To all whom it may concern:

Be it known that I, ROBERT L. GRAY, a citizen of the United States, residing in Newark, in the county of Essex and State 5 of New Jersey, have invented certain new and useful Improvements in Boxes or Cartons for Displaying Merchandise, of which the following is a specification.

My invention relates to an improvement 10 in containers; particularly boxes or cartons to display merchandise to prospective customers.

An object of my invention is to provide a 15 container embracing a body and a cover; the latter being so designed that it can be manipulated to set up the body at an incline on a supporting surface; the container also having means for enabling the cover, when the container is thus set up, to be secured to the 20 body and firmly held in the most advantageous position.

Other objects of my invention will appear 25 from the following description taken in connection with the accompanying drawings, which show the best form of my invention now known to me. This disclosure, however, is explanatory only, and I reserve the right to vary the construction actually illustrated, within the scope and spirit of my invention, to the full extent indicated by the 30 general meanings of the terms in which the appended claim are expressed.

On the drawings:

Figure 1 is a plan view of a blank from 35 which a box or carton can be made according to my invention;

Fig. 2 is a perspective view of the complete box with the cover in closed position; and

Fig. 3 is a perspective view of the container set up to display the contents.

The same numerals of reference identify the same parts throughout.

For the blank shown in Fig. 1 I prefer to 45 utilize cardboard; but obviously other material can be employed. Further, while my invention is set forth as produced from a blank in one piece, I may also make the container in several pieces, united by pasting or 50 otherwise, as will be understood.

As illustrated, the blank includes a portion 55 1 for making the body of the container; and a portion for making the lid or cover 2. These two portions are marked off from each other by a transverse crease or score line 3,

which provides a hinge, in effect; and enables the cover to close the box or open it. The portion 1 has a section 4 for making the bottom of the container, sections 5 with extensions 6 for the sides, and sections 7 with extensions 8 for the ends. Similar sections 5 with extensions 6 and a section 7 with extensions 8 are comprised in the portion making the cover 2; but the sides of the lid or cover are shorter than the sides of the body 65 and begin at points a short distance from the score line 3.

The sections 5 of the body are marked off from the bottom 4 by longitudinal score lines 9, similar to the line 3; and other score lines 70 9 extend across the portion 1 to mark off the ends 7. Similar lines mark off the extensions 6 and 8 from these sides 5 and ends 7. In the same way I mark off the sides 5 and end 7, with their extensions 6 and 8, of the 75 lid or cover of the container.

To give the box its proper form the ends 7 of the portion 1 are bent up at a right angle to the bottom 4, and the extensions 8 of the ends are bent till the extensions of each 80 end extend toward those of the other. Next the sides 5 are bent up, and their extensions 6 folded downward and inward over the extensions 8. To hold the sides, I provide tabs 10 cut from the bottom 1. These tabs are 85 pushed up slightly when the extensions 6 are folded down over the extensions 8, so that the extensions 6 can go down all the way to the bottom 1; when the tabs are released and made to abut against the extensions 6, so as to prevent the extensions 6 from 90 springing back out of place, and letting the ends 7 become loose. Thus the extensions 8 are gripped between the sides 5 and extensions 6; and the sides and the ends 95 are thus held in the required relations. The end and sides of the cover are manipulated in the same manner, and the cover can be opened by turning it about the line 3, or turned to close the body as indicated in 100 Fig. 2.

Other ways of causing the sides and ends of the body and the cover to engage each other can of course be adopted, but as an example the method just described will 105 suffice.

To set up the container, the cover is made so that it can be folded on a transverse line between its ends, as well as turned about the line 3. For this purpose the sides of the 110

cover are not of the same length as the cover; but extend from the free end of the cover to points at some distance from the score line 3, as above stated. At the points in question 5 I provide a couple of short score lines 11, these lines extending inward along the top part of the cover a short distance. Between the inner ends of the lines 11, the top of the cover is cut through along a line 12. The 10 top of the cover is thus divided into a shorter section between the lines 11 and the line 3; and a longer section between the lines 11 and the end 7; and the cover can be folded by bending it along the transverse line determined by the score lines 11 to bring these 15 two sections nearly together.

The manner of folding the cover to set up the container to display the contents is shown on Fig. 3. As indicated in that view, 20 the two sections of the cover can be folded along the lines 11, and turned about the line 3 into an upright position; the longer section of the cover being thus turned down at the adjacent or rear end of the body; 25 extending across this end and holding the body at an incline to the surface that supports the container. The shorter portion of the cover between the line 3 and the lines 11 and 12 will then constitute a panel to receive advertising matter; and the line 12 may be cut in such a way as to give the top of this panel above and between the lines 11 any fanciful or ornamental outline or configuration.

35 With the body at an incline, the longer section of the cover will be substantially perpendicular to the supporting surface. Hence this longer section will not be disposed flat against the adjacent end 5 of the body, but will make contact therewith along the lower edge only. The two sections of the cover and the adjacent or rear end of the body will thus inclose a space having substantially the form indicated in Fig. 3; 40 this space being three-cornered when the lower edge of the rear end of the body and the longer section of the cover are in actual contact. Such contact, however, is not necessary, as the longer section of the cover 45 and the rear end of the body may be out of contact, and the container made to set up just as well.

When the body is at an incline, and the shorter section of the cover slants backward 55 slightly, and the longer section of the cover is substantially perpendicular to the supporting surface, the container will be in the most advantageous position both to display the goods in it and to be prevented from 60 falling or allowing the body to collapse or sink down flat on the supporting surface, due to the weight of the contents or to handling. To hold the cover and body firmly together in these relative positions the container is provided with suitable means pref-

erably in the form of tongues 13 in the longer section of the cover adapted to extend out from this section and be inserted into the rear end of the body at both sides thereof. These tongues are located near 70 the score lines 11, being cut free from the cover along their sides and at one end, and being hinged to the cover at their opposite ends. When the cover is closed, these tongues lie in the plane of the top part of 75 the same, as in Fig. 2; but when the container is set up, the tongues are pushed out by the operator's fingers and inserted in between the sides 5 and the extensions 8 of the adjacent end 7 of the body. The tongues 80 13 will fit tightly enough into the body to afford the results aimed at.

The tongues 13 are cut and shaped in such a way that the lower edges of these tongues, when the container is set up, will 85 make the same angle with the horizontal as the angle of incline of the body of the box. The upper edges will be parallel to the lower edges, not all the way from the ends of the tongues to the cover, but only as far 90 as shoulders 14 at the hinged ends of the tongues. These shoulders make the tongues wider adjacent their hinged ends, so that they cannot be inserted into the body over their full lengths. Hence, when the 95 shoulders reach the body, the tongues must stop. These tongues are an important feature of my invention because they insure correct perpendicular position for the longer section of the cover on the supporting surface when the container is set up to display the goods it is filled with. If the shoulders 14 were omitted, so that the tongues could be inserted into the ends of the sides of the body over the full lengths 100 of their edges, the lower section of the cover could be disposed flat against the rear end of the body; and in consequence, when the container is set up, both the body and the cover would be at an incline, and the body 105 through handling by purchasers would often collapse. The proper use of the container would thus be interfered with and the efficiency of the container reduced; especially when the container is set up by careless 110 dealers. The shoulders 14, however, obviate the risk of any one setting up the container 115 in the wrong manner.

It will be observed that, when the container is set up, the plane of the tongues 13 120 will be perpendicular to the plane of the supporting surface, the same as the longer section of the cover.

The container is intended for counters, windows, etc., in stores and other places, 125 and is both simple and easy to operate, and makes the goods conspicuous and presents a very attractive general appearance.

Having described my invention, what I believe to be new and desire to secure and 130

protect by Letters Patent of the United States is;—

A container embracing a body with a cover hinged thereto, the cover being adapted to be folded on a transverse line and be turned to enable the body to be set up on a supporting surface to display the contents, the cover having tongues at its sides to be bent away from the cover and inserted into the adjacent ends of the sides of the body, said tongues having shoulders to prevent the insertion of the full lengths of the tongues into the body, and provide a space between the folded cover and the adjacent

end of the body, whereby the container may 15 rest on said surface with the body at an incline and the section of the cover between said line and the free end of the cover firmly held in substantially perpendicular position with respect to said surface, the 20 plane of said tongues also being perpendicular to said surface when inserted into said body.

In testimony whereof I have signed my name to this specification this 8th day of 25 August, 1918.

ROBERT L. GRAY.
